UNITED STATES PATENT OFFICE

KENNETH G. MCKIERNAN, OF CHICAGO, ILLINOIS, ASSIGNOR TO GEO. F. MCKIERNAN & CO., OF CHICAGO, ILLINOIS, A CORPORATION OF ILLINOIS

ADVERTISING FOLDER

Application filed July 5, 1928. Serial No. 290,475.

My invention relates to advertising folders and particularly to advertising folders adapted to be mailed. One object of my invention is the provision of such a folder which will disclose a sample of the article or goods being advertised. Another object is the provision, in connection with a mailing folder, of means for displaying the article or goods sold in a simulation of its position when in use. Another object is the provision of an advertising or display folder which shall display the article or goods being advertised and shall also provide graphic demonstration of its use together with descriptive material. Another object is the provision of an advertising or display folder which when folded will be ready to be addressed and mailed.

Other objects will appear from time to time in the course of the specification and claims.

I illustrate my invention more or less diagrammatically in the accompanying drawings, wherein—

25 Figure 1 illustrates the folder blank in open position;

Figure 2 illustrates the blank partly folded;

Figure 3 is a top plan view of the folder in 30 the closed and sealed position;

Figure 4 is a section along the line 4—4 of Figure 3;

Figure 5 is a section along the line 5—5 of Figure 3; and

35 Figure 6 is a perspective view of the folder addressed for mailing.

Like parts are indicated by like symbols throughout the specification and drawings.

Referring to Figure 1, which illustrates the 40 folder or the folder blanks in extended position, A generally indicates a central portion of the blank in the form of a rectangle which may carry, for example adjacent its bottom, a sample A¹ of the goods being advertised.

45 It may carry for example, a display or sample of felt adapted to be positioned beneath a rug, although it will be understood that I do not wish to limit myself to the display of any specific article or goods except so far 50 as limited thereto by the precise language of

my claims. A² indicates descriptive material or text on the portion A of the blank which may refer to the sample A¹ displayed.

Continuing the blank A at each long side thereof are the extensions B, B¹. In case the sample A¹ is of considerable thickness the sections B B¹ may be joined to the central section A by intermediate side members B² which increase in width from the top to the bottom of each side of the member A..

The member B¹ may carry on its inner face any suitable text B³ and preferably is apertured as at B⁴, such aperture overlying the sample A¹. On the opposite side of the blank B¹ I may indicate as at B⁵ any suitable design which is built around the aperture B⁴. I illustrate for example a carpet which includes the cut away portion or aperture B⁴ which therefore discloses, as part of the carpet the sample A¹. A vacuum cleaner is included in the representation B⁵ to indicate that the felt may be cleaned by a vacuum cleaner. The blank B may be provided on its inner side with any suitable text B⁶ and may carry, if desired, the return postcard B⁷. It is further apertured as at B⁸ in such fashion that the apertures B⁴ and B⁸ overlap or overlie each other when the portions B B¹ are folded together over the central portion A.

The opposite side of the blank B, may carrying any suitable representation as at B⁹ in which the aperture B⁸ is included to illustrate the sample A¹ as part of the representation.

Along the lower edge of the central portion A I show a tab or tongue C connected to it by the intermediate or connecting hinge portion C¹. When the device is ready to be mailed the portions B, B¹ are folded over each other and over the central portion A in such fashion that the apertures B⁴ and B⁸ overlie. The tongue C is then inserted through the aperture, thus locking or closing the assembled folder. If desired a sticker C² may be employed to complete the closure and the device is ready to be addressed and mailed. The sticker and the tongue may both be used or, if desired, the tongue may be eliminated, the sticker C², or any other 100

suitable securing means, being employed to hold the device closed.

It will be realized that whereas I have described and shown a practical and operative device, nevertheless I wish my description and drawings to be taken as in a broad sense illustrative and diagrammatic rather than as limiting me specifically to the shape and proportions or to the location and shape of apertures or to the designs or representations employed. Many modifications or changes may be made without departing from the spirit of my invention.

I claim:

15. 1. In an advertising folder, a central section, a plurality of overlapping side sections hinged along opposite edges of the central section, a tongue member hinged along another edge of the central section, the first 20 mentioned overlapping members being apertured, the apertures being positioned to overlie each other when the folder is folded together, the tongue being adapted to be inserted through said apertures and to hold 25 the folder closed, and a sample of the goods being advertised associated with the folder and positioned to underlie the apertures when the folder is folded together.

2. In an advertising folder, a central section, a plurality of overlapping side sections hinged along opposite edges of the central section, a tongue member hinged along another edge of the central section, the first 30 mentioned overlapping members being apertured, the apertures being positioned to overlie each other when the folder is folded together, the tongue being adapted to be inserted through said apertures and to hold the folder closed, a sample of the goods being 35 advertised associated with the folder and positioned to underlie the apertures when the folder is folded together, and pictorial designs on said side sections which incorporate the exposed portion of the sample.

40. 3. In an advertising folder, a central section, a plurality of overlapping side sections hinged along opposite edges of the central section, a tongue member hinged along another edge of the central section, the first 45 mentioned overlapping members being apertured, the apertures being positioned to overlie each other when the folder is folded together, the tongue being adapted to be inserted through said apertures and to hold the folder closed, and a sample of the goods being 50 advertised associated with the folder and positioned to underlie the apertures when the folder is folded together, the folders and the sample being positioned adjacent the end 55 of the folder where the tongue is located.

4. In an advertising folder, a central section, a plurality of overlapping side sections hinged along opposite edges of the central section, a tongue member hinged along another edge of the central section, the first 60

70 mentioned overlapping members being apertured, the apertures being positioned to overlie each other when the folder is folded together, the tongue being adapted to be inserted through said apertures and to hold the folder closed, and a sample of the goods being advertised associated with the folder and positioned to underlie the apertures when the folder is folded together, the folders and the sample being positioned adjacent the end of the folder where the tongue is located, the side sections being connected to the central section by intermediate hinged sections 75 adapted to compensate for the thickness of the sample.

5. In an advertising folder, a central section, a plurality of overlapping side sections hinged along opposite edges of the central section, a tongue member hinged along another edge of the central section, the first 80 mentioned overlapping members being apertured, the apertures being positioned to overlie each other when the folder is folded together, the tongue being adapted to be inserted through said apertures and to hold the folder closed, and a sample of the goods being 85 advertised associated with the folder and positioned to underlie the apertures when the folder is folded together, the folders and the sample being positioned adjacent the end of the folder where the tongue is located, the side sections being connected to the central section by intermediate hinged sections adapted to compensate for the thickness of the sample, and increasing progressively in 90 width from the end of the folder farthest from the tongue and sample.

95. 6. In an advertising folder, a central section, a plurality of overlapping side sections hinged along opposite edges of the central section, the overlapping sections being apertured, the apertures being positioned to overlie each other when the folder is folded together, and means for holding the folder so formed closed, and a sample of the goods being 100 advertised associated with the folder and positioned to underlie and appear through the above mentioned apertures when the folder is folded together, and a tongue adapted to penetrate said apertures and to hold said 105 overlapping sections in position above the central section, and to overlie said sample.

110. 7. In an advertising folder, a central section, a plurality of overlapping side sections hinged along opposite edges of the central section, the overlapping sections being apertured, the apertures being positioned to overlie each other when the folder is folded together, and means for holding the folder so formed closed, and a sample of the goods being 115 advertised associated with the folder and positioned to underlie and appear through the above mentioned apertures when the folder is folded together, and a tongue adapted to penetrate said apertures and to 120

125

130

hold said overlapping sections in position above the central section, and to overlie said sample, and pictorial designs on said side sections which incorporate the exposed portion of the sample.

5 Signed at Chicago, county of Cook and State of Illinois, this 29th day of June, 1928.

KENNETH G. McKIERNAN.
